United States Patent

Des. 235,081
Patented May 6, 1975

235,081

BED PAN

Julia Gatewood, 18 Pinetop Drive,
Central Islip, N.Y. 11722

Filed Oct. 29, 1973, Ser. No. 410,975

Term of patent 14 years

Int. Cl. D24—04

U.S. Cl. D83—1 U

FIG. 1

FIG. 2

FIG. 3

FIG. 4

FIG. 5

FIG. 1 is a top plan view of a bed pan showing my new design;

FIG. 2 is a side elevational view thereof;

FIG. 3 is an end view looking at the right hand end of FIG. 1;

FIG. 4 is an end view looking at the left hand end of FIG. 1; and

FIG. 5 is a bottom plan view thereof.

I claim:

The ornamental design for a bed pan, substantially as shown.
